ATTORNEY

UNITED STATES PATENT OFFICE

CORRIE F. RUDOLPH, OF WASHINGTON, DISTRICT OF COLUMBIA

COUPLING DEVICE FOR HIGH FREQUENCY APPARATUS

Application filed March 8, 1930. Serial No. 434,233.

My invention relates broadly to high frequency signaling apparatus and more particularly to a flexible insulated coupling for the control of moving parts in high frequency telegraph apparatus.

One of the objects of my invention is to provide an improved insulated flexible coupling construction for the rotative control of high frequency signaling apparatus.

Another object of my invention is to provide a construction of insulated joint for a rotary shaft in a high frequency telegraph signaling apparatus.

A further object of my invention is to provide a construction of insulated coupling in which an insulated rod of high dielectric strength is counterbored at each end thereof to receive portions of a controlled shaft and a controlling shaft with sufficient clearness to permit the necessary vertical and horizontal alignment of the apparatus which is controlled with respect to the position of the controlling member.

Other and further objects of my invention reside in the construction of insulated coupling device as set forth more fully in the specification hereinafter following by reference to the accompanying drawing, in which:

Figure 1 is a side elevational view illustrating the coupling device of my invention partially broken away and illustrated in cross-section with the length thereof counter-shortened for purposes of illustration; Fig. 2 is a plan view of the insulated coupling illustrated in Fig. 1; Fig. 3 is a cross-sectional view through one of the connecting shafts which extends into the counterbored portion of the insulated coupling; and Fig. 4 is a perspective view of the insulated coupling member of my invention.

In high frequency signaling apparatus such as short wave radio telegraph transmitters, a high degree of insulation is necessary to secure high efficiency of the operation in the apparatus. In mounting rotary mechanism in the transmitter, precaution must often be taken to insulate the transmitting apparatus per se from the front panel structure of the apparatus. The adjusting shaft mechanism which operates the adjust-

able inductance, capacity, or contact system in a short wave transmitter is insulated from the adjusting means according to my invention by a shaft member of isolantite or other insulation material having a high dielectric strength and serving as a good insulator with respect to high frequency currents in the transmitter circuits. An insulated shaft is counterbored at opposite ends to receive the ends of the controlled shaft and the controlling shaft, which shafts are locked with respect to the insulated coupling by pin members which extend through the counterbored portions of the shaft. Sufficient clearance is provided in each end of the insulated coupling to permit the necessary vertical and horizontal alignment of the controlled and controlling shafts.

The coupling construction of my invention will be more clearly understood by detailed reference to the drawing wherein reference character 1 designates the insulator which is capable of outstanding high frequency voltages or fields. The insulator 1 is preferably circular in cross-section and is counterbored at 2 in each end thereof, the depth of the counterbored portion being selected in accordance with the requirements to which the insulator may be placed, but usually the coupling is constructed precisely the same on each end thereof and the depth of the counterbored portions 2 is the same on each end of the coupling. I have illustrated the insulated frame 12 of the high frequency signaling apparatus which may be, for example, the end support for an inductance, the turns of which are carried by the insulated struts 14. A bearing 15 is carried in frame 12 through which tubular member 16 passes and within which there is mounted the rotary shaft 17 provided with screw 18 thereon which may control rotary mechanism actuating an adjusting mechanism for the short wave transmitting apparatus. The shaft 17 has an end portion 3 thereon which is diametrically slotted as indicated at 3a. By reason of the counterbored portions 2 of the insulator 1, there is provided at each end of the insulator a shell-like wall 1a housing the ends of the controlled shaft 3 and the

controlling shaft 4. The controlling shaft 4 is provided with a diametrically extending slot 4a in the end thereof similar to the slot 3a in the shaft 3. The insulator 1 is diametrically apertured at 7 and 8 through shell portions 1a at each end thereof. The apertures at one side of the insulated shaft are smooth walled. The apertures on the opposite side of the shaft are screw threaded as indicated at 7a and 8a, enabling the pins 5 and 6 having screw threads 5a and 6a on the ends thereof to pass through the smooth walled apertures and to engage the screw threaded apertures in the wall 1a, thereby establishing diametrical members across the sockets 2 into which the shafts 3 and 4 may interlock. The screws 5 and 6 are each provided with adjusting heads 5b and 6b which fit flush with the cylindrical surface of member 1 so that the insulator is interlocked with the opposite directed shafts 3 and 4 without portions of the insulator projecting beyond the cylindrical contour thereof. The controlling mechanism for effecting adjustment of the shaft 17 is mounted upon panel 20 which carries the frame 21 in which shaft 22 is journaled, the shaft being connected with crank 23 controlled by handle 24. A bevel gear 25 is carried by shaft 22 and meshes with bevel gear 26 for driving the counter 27 indicating the adjustment of the rotary shaft mechanism by readings visible through the front of the panel 20. The pins 5 and 6 form a solid union between projecting shafts 3 and 4 and the insulated coupling as the pins are smooth and are turned to a snug fit in the diametrical slots in the ends of shafts 3 and 4. This arrangement permits a universal action of the joint with no back-lash which is very necessary for close calibration of the frequency adjusting apparatus of a transmitter where inaccuracies in alignment of the controlled shaft and controlling shaft normally occur.

The isolantite insulator resembles porcelain and provides insulation of high dielectric properties. Other forms of insulation may be used other than isolantite where such insulation is of high dielectric strength with respect to high frequency currents.

While I have described my invention in certain preferred embodiments, I desire that it be understood that modifications may be made and that no limitations upon my invention are intended other than are imposed by the scope of the appended claims.

What I claim as new and desire to secure by Letters Patent of the United States is as follows:

1. In high frequency signaling apparatus, a frame, a panel spaced from said frame, a driven shaft rotatably mounted and projecting through said frame towards said panel, a driving shaft rotatably mounted through said panel and extending towards said frame

substantially in axial alignment with the driven shaft and spaced well away from the same, facing ends of the shafts being each formed with a diametrically extending slot opening through its end and sides, a solid insulator formed of material having high dielectric strength extending between said shafts and having axially extending sockets leading from its ends and loosely receiving the slotted end portions of said shafts to permit side play, the distance between the sockets being appreciably greater than the depth of the sockets to provide a good insulation between the shafts, opposed wall portions of the sockets being formed with openings, and pins extending transversely through the sockets with their ends engaged in the openings and their intermediate portions extending through the slots of the shafts and frictionally engaging walls of the slots in spaced relation to their inner ends.

2. In electrical apparatus, a frame, a driven shaft journaled in said frame, a panel, a driving shaft extending through said panel and supported thereby substantially in axial alignment with said driven shaft, said shafts having diametrically extending openings from side to side near their opposing ends, a solid insulator formed of material having high dielectric strength and provided with sockets receptive of the ends of said shafts, pins extending transversely through said sockets and firmly secured in the insulator walls which surround said sockets, means including a solid central portion of said insulator for maintaining a high degree of insulation between said shafts' ends, and means including said pins and the closely fitting walls of said shaft openings for rendering said insulator substantially a universal joint between said driving and said driven shaft and for reducing back-lash to a minimum.

CORRIE F. RUDOLPH.
